UNITED STATES PATENT OFFICE

2,406,169

PUSHCART

Guarling F. Sirman, North Miami, Fla.

Application July 24, 1945, Serial No. 606,744

2 Claims. (Cl. 280—58)

1

This invention relates to wheeled vehicles such as push carts, barrows and the like and has for one of its objects to improve generally upon this type of vehicle.

Another object is to produce a device of this kind having a relatively low wheel base with the bottom of the body or the platform part of the device and the handle members arranged in a definite correlated angularity with respect to each other and in a general plane in proximity to the periphery of the ground wheel or cylindrical supporting roller so as to afford easy handling of the device as well as a convenient placement of the handle members so that the device may be pushed or pulled with minimum physical effort on the part of the operator.

Other objects and advantages to be attained will hereinafter more fully appear in the following description.

An illustrative but non-limiting practical exemplification of the invention is illustrated in the accompanying drawing, in which:

- Figure 1 is a top plan view;
- Figure 2 is a side elevational view;
- Figure 3 is a forward end view;
- Figure 4 is a rear end view; and
- Figure 5 is a longitudinal section on the line 5—5 and on a somewhat enlarged scale.

Referring now to the drawing in detail, the numeral 6 designates, generally, the main body portion of the device which, as shown, is of the plain platform type. However, as far as the present invention is concerned, the body may include side and end walls (not shown) which may be either fixedly secured to the platform or bottom portion 6 or provided and arranged so as to be detachable therefrom.

Instead of the usual narrow rimmed wheels a cylindrical hollow roller 7 is provided. This roller may be made of any suitable material, but as shown it is made of wood. The same may be constructed in any suitable or approved manner. As shown, it comprises circular end heads 8 built up of strips or segments placed edgewise together and, preferably, each in double thickness with the strips or segments of the one layer disposed cross-wise with relation to the other layer. So, too, the heads 8 may be constructed in any other laminated or in a single piece form. The peripheral portion of the roller 7 may be built up of elongated rectangular strips or staves 9 and nailed or otherwise fastened at their ends to the heads 8 by nails or other suitable securing means.

The body or platform portion 6 is provided at its opposite longitudinal sides with cleats 10 on

the under side thereof. Secured on the inner sides of the forward end portions of said cleats 10 are angular struts 11 which incline inwardly and downwardly from said end portions of the cleats 10. These struts 11 are of a length so that their lower ends terminate so as to be secured to the upper side of the forward end portions of elongated frame members 12 which are extended beyond the rear end of the body or platform 6 to constitute handle members 13, the free end portions of said handle members 13 being reduced in size and shape to provide convenient hand grips 14.

The inner end portions of the cleats 10 of the body or platform portion 6 are extended some distance so as to be secured on the outside of the adjacent intermediate portions of said integral frame side members 12 and handle extensions 13, as at 15 (see Figure 2). Extending downwardly from the side frame members 12 at transversely opposite places where the platform 6 terminates at its inner end and the handle extensions 13 continue therefrom is a pair of supporting legs 16. These legs 16 extend perpendicularly from the members 12 so that when the leg members are supported with their lower ends on the ground they are disposed at a slight inclination instead of being directly vertical. Diagonal side brace members 17 are attached at their forward ends to the corner portion of the side framing adjacent the forward end of the platform 6, as at 18, and their lower inner end portions are attached to the lower end portions of said leg members 16, as at 19, the intermediate portion of the members 17 crossing the members 12 and being secured thereto as at 20.

The forward strut members 11 are cross-connected by a transverse brace member 21 which is fastened at its ends to the outer face portions of said members 11 and it extends parallel adjacent to the forward edge portion of the platform 6. The lower end portions of the supporting legs 16 are cross-connected by a transverse brace 22 and said legs 16 are also cross-connected by a diagonal brace 23 which is attached, as at 24, to the lower end portion of the left leg 16 and closely contiguous to the adjacent end of the cross brace 22 and its opposite upper end portion is attached to the right leg 16, as at 25, closely adjacent the under side of the companion side frame member 12.

The cylindrical ground roller 7 may be mounted on the side frames of the device in any suitable or approved manner. As shown, the roller 7 is provided with a shaft 26 which extends axi-

ally therethrough, and is of a length to project some distance at its opposite ends beyond the adjacent heads 8 of the roller. This shaft 26 is fixedly secured to the roller so as to have no independent movement either longitudinally or rotatively with respect to the roller. That is to say, the shaft and the roller rotate the one by and with the other and also they are fixed to move endwise together. The extreme end portions of the shaft 26 are journaled in a conventional manner in bearing elements 27 secured on the under side of the forward end portions of said side frame members 12.

The device of the present invention is of general utility on the farm and many industries and places of use, and particularly for uses about grounds including lawns in which a narrow rimmed supporting wheel would cut ruts and otherwise mar and damage the surface thereof; but, on the contrary, the supporting roller of the present device can be used to advantage in rolling out any unevenness in the ground or lawn.

From the foregoing it is seen that the wheeled vehicle of the push cart type is produced in a simple, compact and rigid frame structure, with a low center of gravity for the main body portion or platform part of the device and with a roller support of a substantial base transversely of the vehicle and parallel with the axis of the roller support, and with handle extensions of the side frames arranged and disposed for convenient handling and manipulation of the device with an ideal leverage effect of the side frame members 12 and handle extensions 13 thereof, with respect to the axis of the supporting roller 7.

The illustration is but one practical embodiment of the invention and the same admits of considerable modification within the spirit and scope of the appended claims. The invention, therefore, is not limited to the specific construction and arrangement shown.

Having thus described the invention what is claimed is:

1. A wheeled vehicle of the push cart and barrow type, comprising diagonally trussed side frames and a crossed truss member, each frame including an elongated bar element, a portion of which constitutes an elongated handle exten-

sion, each side frame having a strut element inclined downwardly and inwardly from the forward upper corner of the frame and joined to the forward end of the aforesaid elongated diagonal truss element and further including a leg member attached at its upper end to the intermediate part of said elongated diagonal truss member and extending substantially perpendicularly thereto and having its lower end attached to the lower inner end of said crossed truss member of the side frame, a flat main body panel having cleats on its under side and contiguous to its longitudinal side edges, said cleats being respectively secured at their outer ends to the forward upper corners of the side frames and at their inner ends to the intermediate portion of the respective elongated truss elements of the frames and adjacent to the upper ends of said leg members, and an elongated cylindrical roller element disposed transversely of the vehicle and overhung fully by the forward end portion of said main body panel, said roller element having an axle extending therethrough and fixedly attached thereto so as to rotate thereby and therewith, the outer end portions of said axle being journaled in bearings provided therefor on the side frames of the vehicle adjacent the lower forward corners thereof.

2. A wheeled vehicle of the class described, comprising a flat body platform panel, inclined slightly rearwardly and downwardly from its forward end, said body panel being mounted at its opposite longitudinal side edge portions on trussed side frames, said side frames each comprising an elongated diagonal truss member extending rearwardly and upwardly at an incline reversely to but at substantially the same angularity as said body panel, leg members extending downwardly from the inner end portions of said side frames to rest normally upon the ground, and a supporting ground roller extending transversely of the vehicle and disposed inwardly underneath the body panel so as to be completely overhung by the forward end portion of said panel, said ground roller being journaled axially at its opposite ends on said side frames of the vehicle.

GARLING, F. SIRMAN.
